United States Patent Office

Des. 223,498
Patented Apr. 25, 1972

223,498

SUPPORT FOOT FOR FURNITURE OR THE LIKE

Gary R. Daum, Poway, Calif., assignor to Hewlett-Packard Company, Palo Alto, Calif.

Filed May 4, 1970, Ser. No. 22,810

Term of patent 14 years

Int. Cl. D6—99

U.S. Cl. D33—1

Figure 1

Figure 2

Figure 3

Figure 4

Figure 5

FIG. 1 is a rear perspective view of a support foot for furniture or the like showing my new design;

FIG. 2 is a front perspective view thereof;

FIG. 3 is an enlarged, fragmentary top view;

FIG. 4 is an enlarged, fragmentary front view; and

FIG. 5 is an enlarged end view thereof as seen from the right of FIG. 2.

I claim:

The ornamental design for a support foot for furniture or the like, as shown.
